UNITED STATES PATENT OFFICE.

GEORGE W. CHILDS, OF NEW YORK, N. Y.

PROCESS FOR UTILIZING SAPPED TANNING LIQUORS.

No. 881,094.

Specification of Letters Patent.

Patented March 3, 1908.

Original application filed May 16, 1906, Serial No. 317,141. Divided and this application filed July 20, 1906.

Serial No. 327,029.

To all whom it may concern:

Be it known that I, GEORGE W. CHILDS, of New York city, in the county and State of New York, have invented a certain new and useful Improvement in Processes for Utilizing Sapped Tanning Liquors, whereof the following is a specification.

This application is a division of my application Serial #317,141, filed May 16, 1906, which is restricted to a process for treating waste tanning liquors containing mineral acid impurities, as herein contemplated.

It is the object of my invention to utilize the portions of tanning liquors which have become so far sapped *i. e.* deprived of active tannic material, by contact with hides as to be no longer available for tanning in the particular yard in which they have been employed. Such sapped liquors being usually polluted with chemicals introduced thereto or resulting from chemical changes therein, and carrying a large percentage of non-tannic material, are termed "runaway" or "tail" liquors and are ordinarily discharged to waste from the last layer in which they have been sapped. For instance, a typical ordinary acid tanning yard *i. e.* a yard where sulfuric or other mineral acid is employed to plump the hides, would comprise five or more layers or vats containing bodies of tanning liquors of different strengths, the strongest of which would be supplied with tanning liquors of approximately 35 degrees barkometer, which primarily strongest liquor when sapped by the hides in the last layer would be supplied to the first or other layers of less strength, and thus used until its proportion of tannin is so low and its proportion of non-tannic elements (both organic and non-organic) is so high that its use is no longer economical, because of its slow action upon the hides, and it is discharged to waste regardless of its tannin value. Similarly, a typical ordinary non-acid tanning yard *i. e.* a yard wherein the hides are plumped without the employment of mineral acid, would comprise a series of five or more layers, the strongest of which would receive a tanning liquor of from 16 degrees to 35 degrees barkometer, which being sapped and transferred to weaker layers or handlers, would be discharged to waste from the weakest layer at from 8 degrees to 10 degrees barkometer, then containing a large proportion of non-tannic ingredients (both organic and non-

organic) and such a small proportion of tannin that its use is no longer economical. Such spent or runaway liquors are impregnated with some or all of the following non-tannic ingredients:—lime, lime compounds, volatile and non-volatile acids and organic filth. The presence of an excessive amount of any such impurities always interferes with the action of the tannin on the hides, and particularly when the tanning liquor has been depleted by contact with the hides; so that although said spent liquors contain more or less tannin, the latter is unavailable for further action on the hides and the liquor containing it must be discarded with consequent loss to the tanner. In accordance with my present process, as hereinafter described, such runaway or tail liquors may be purified and concentrated to from 1.05 to 1.3 specific gravity and thereby made available for further tanning purposes.

The purification above contemplated may be effected as follows:—If the spent liquor contains lime or lime compounds these constituents may be precipitated by the addition of chemicals forming insoluble compounds with lime. For instance, ammonium oxalate, sodium phosphate, sodium fluorid, or carbon dioxid gas may be employed to effect such precipitation. The precipitate is then settled out and the supernatent liquor run off for further purification or concentration. If the liquor contains non-volatile acids, these may be either neutralized by the addition of alkali, or the acids may be precipitated by the addition of bases forming insoluble compounds with the acids. Spent liquors partially purified as aforesaid may then be concentrated to form 1.05 to 1.3 specific gravity for the purpose of removing volatile impurities and with the effect of reducing the liquors to a form in which the otherwise useless tannin therein becomes available. Of course, such reduction in the bulk of the purified liquors also facilitates their transportation. The otherwise waste liquors thus purified and concentrated may be utilized as follows:—Hides which have been treated in vats with a tanning solution until they are colored through, are then impregnated with a concentrate obtained as above described. For instance such leather may be placed in a rotary drum and said concentrate, preferably heated, introduced to said drum, conveniently through a hollow

axle or trunnion thereof, and the revolution of said drum continued until the leather absorbs the concentrate which combines with and colors the leather. It may be observed that if said liquors were not concentrated to substantially the consistency described, there would not be sufficient solid residue thereof when the leather is dried, to obtain the result desired. Moreover, if the liquors were concentrated to a greater degree they would not be absorbed by the leather. Leather treated as last described may then be bleached, oiled, dried, dampened and rolled in the usual manner.

I do not desire to limit myself to all of the details of procedure above enumerated, as various modifications may be made therein without departing from the essential features of my invention. For instance, some waste liquors will require all of the above purifying steps, others will require some, and

in a few cases concentration of the waste liquor to the proper consistency will be all that is required to remove volatile matters and make the tannin active and available.

I claim:

1. The process which consists in impregnating leather with concentrated waste tanning liquor.

2. The process which consists in impregnating leather with concentrated waste tanning liquor heated above atmospheric temperature, and when the leather is still moist from the tanning process.

In testimony whereof, I have hereunto signed my name at New York city in the county of New York and State of New York this 18th day of July 1906.

GEORGE W. CHILDS.

Witnesses:

W. G. HORTON,
F. P. PALMER.

Correction in Letters Patent No. 881,094.

It is hereby certified that in Letters Patent No. 881,094, granted March 3, 1908, upon the application of George W. Childs, of New York, N. Y., for an improvement in "Processes for Utilizing Sapped Tanning Liquors," an error appears in the printed specification requiring correction, as follows: In line 94, page 1, the word "form" should read *from*; and that the said Letters Patent should be read with this correction therein that the same may conform to the record of the case in the Patent Office.

Signed and sealed this 24th day of March, A. D., 1908.

Correction in Letters Patent No. 881,094.

It is hereby certified that in Letters Patent No. 881,094, granted March 3, 1908, upon the application of George W. Childs, of New York, N. Y., for an improvement in "Processes for Utilizing Sapped Tanning Liquors," an error appears in the printed specification requiring correction, as follows: In line 94, page 1, the word "form" should read *from*; and that the said Letters Patent should be read with this correction therein that the same may conform to the record of the case in the Patent Office.

Signed and sealed this 24th day of March, A. D., 1908.

[SEAL.]

C. C. BILLINGS,

Acting Commissioner of Patents.
